UNITED STATES PATENT OFFICE.

RONENA C. WEBSTER, SR., OF LIPSCOMB, TENNESSEE.

PUBLIC-HALL EXIT.

SPECIFICATION forming part of Letters Patent No. 290,951, dated December 25, 1883.

Application filed October 8, 1883. (No model.)

To all whom it may concern:-

Be it known that I, Miss RONENA C. WEBSTER, Sr., a citizen of Tennessee, United States, residing at Lipsecomb, in the county of Maury 5 and State of Tennessee, have invented certain new and useful Improvements in Public-Hall Exits; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to means whereby a series of doors can be simultaneously opened by one person, and is particularly designed for public buildings; and it consists in the construction and arrangement of parts, as will be 20 more fully set forth and claimed.

In the accompanying drawings like letters of reference indicate like parts in the several figures.

Figure 1 represents a wall of a building 25 partly broken away, with two sliding doors and means for opening them when their fastening latches or bolts are released. Fig. 2 represents a sectional view taken on the line $x-x$ of Fig. 1. Fig. 3 is a detail showing means 30 for hanging said doors. Fig. 4 is a plan view, partly in section, of a building with the flooring broken away to show the means for unfastening the doors. Figs. 5, 6, and 7 are details, which will be presently described.

35 It is well known that much of the loss of life and serious bodily harm which are caused by the efforts of people to escape from places in which they have assembled for amusement or instruction might be avoided if a suitable 40 number of exits were provided which could be simultaneously opened by one person.

By my improvement it will be seen that the places of exit, most of which are usually locked until the audience is about to disperse, can be 45 opened at once by any one having knowledge of the facilities for unfastening the doors.

In carrying out my invention I use a hollow wall, A, as will be seen in Figs. 2 and 4,

with or without a track, a. This track is adapted to fit in a groove in the bottom of the door 50 in the ordinary way.

Just above the door I have suspended a rail, B, upon which the door B' is suspended by means of rollers a', as clearly shown in Fig. 2, and which means is in common use.

55 At some distance from the door a pulley, b, is secured to the wall, over which passes a rope, b', one end of which is secured to the door, and the opposite end has a weight, b''. The weight is sufficient to open the door when 60 unfastened, and a single weight can be made to open a series of doors, if desired.

Under the flooring of the audience-room of the building is a rod, C, which passes through a collar, c, on the crank-shaft E, to which it is 65 secured by a thumb-screw, c'. The rod C is turned up through a slot in the floor, and is provided with an operating-handle, C'. The shaft E is mounted upon a suitable number of bearings, and has central and end cranks, e e', 70 which are provided with guiding-plates within the hollow wall, and are held down by the action of springs f, which are overcome in raising the catches f' by means of the cranks e'. 75

At the end doors I employ a bell-crank, H, to one arm of which the rod C is hinged, the other arm being connected to the catch-rod F f'. The rod C is provided with a strong spring, G, which readjusts the catches in position to 80 receive the latches when the doors are closed.

It will be readily seen that when the doors are in a closed position, by simply pulling back the lever C the latches of the end and side doors will be simultaneously released. 85

I am aware that changes in the form, proportion, and number of the parts herein specifically described, as showing an embodiment of my invention, can be made without departing from the principle or sacrificing the 90 advantages thereof—as, for instance, more than one crank-shaft may be required, and the means for connecting the rod C to the shaft E can be changed. I would therefore have it understood that I do not limit myself to the exact 95 construction shown and described, but hold

myself at liberty to make such changes and alterations as fairly fall within the scope of my invention.

My device can be applied to buildings having solid walls by building an inner wall, or the catches can be adapted to catch the latches of hinged doors.

I claim and desire to secure by Letters Patent—

The rod C and crank-shaft E e', in combination with the spring G, spring-catch rods

F f f', bell-crank H, and a series of doors, with means for automatically opening them when their latches are released, substantially as shown and described.

In testimony whereof I affix my signature in presence of two witnesses.

R. C. WEBSTER, Sr.
